DESCRIPTION

U.S. PATENT DOCUMENTS

FIG. 1 is a perspective view of a linear type light emitting diode assembly showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom side elevational view thereof; and,

FIG. 7 is a top side elevational view thereof.
